UNITED STATES PATENT OFFICE

2,648,824

MULTIBAND TUNER

Vincent P. Friberg, Lyndhurst, N. J., assignor to
 Automatic Manufacturing Corporation, Newark, N. J., a corporation of New Jersey

Application January 16, 1951, Serial No. 206,245

19 Claims. (Cl. 336—77)

1

This invention relates to a multi-band tuner and more particularly to a device for continuously varying the resonant frequency of a tuned circuit over two different frequency bands which may be immediately tuned adjacent or separated.

Tuned circuits comprising an inductance and a condenser or comprising an inductance which resonates with its distributed capacity are well known. It is also known to tune such circuits by varying the condenser or by varying the reactance of the inductance with a movable magnetic core. However, in the past it has been difficult to tune such circuits over a wide frequency band and to tune such circuits over two different frequency bands without the use of complicated mechanical arrangements, such as separate band switches, rotary turrets or manually replaceable components.

It is an object of my invention to provide a multiband tuner which is simple and which is economical to manufacture.

It is a further object of my invention to provide a multi-band tuner which is simple to operate, which is stable in operation and which requires only a single tuning control for operation over a plurality of frequency bands.

Other objects and advantages of my invention will be apparent from the detailed description of the invention given hereinafter by way of example only and setting forth the manner in which I now prefer to practice the invention.

In accordance with my invention, a core, one portion of which is magnetic but of low conductivity and another portion of which is highly conductive, is mounted adjacent a coil or coils having the shape of a portion of a toroid. As the core is moved relative to the coil or coils or vice versa, the reactance of the coil or coils is varied, and a switch associated with the core adjusting mechanism changes the portion of the coil or the particular coil which is operative in the tuned circuit.

In accordance with the preferred embodiment of my invention, the core is toroidal in shape and the entire core is formed from a magnetic composition, such as powdered iron embedded in thermo-plastic material. A portion of the core is coated with a conductive layer, such as silver. The core passes through a pair of coils which have the shape of a portion of a toroid, and both of which are operative when the magnetic, low conductivity portion is therein and when the magnetic, low conductivity portion is within one coil and the conductive portion is within the other coil but only one of which is operative when the conductive portion is within the other coil.

2

My invention may be better understood by referring to the following detailed description of the invention and to the accompanying drawings, in which:

5 Fig. 1 is a side elevation view of one embodiment of my invention;

Fig. 2 is an end elevation view partly in section of the embodiment shown in Fig. 1 and taken along the line 2—2 indicated in Fig. 1;

10 Fig. 3 is an end elevation view partly in section of the embodiment shown in Fig. 1 and taken along the line 3—3 indicated in Fig. 1;

Fig. 4 is a fragmentary sectional view of a coil form support employed in my invention taken along the line 4—4 indicated in Fig. 3;

15 Fig. 5 is a fragmentary sectional view of a magnetic core employed in my invention taken along the line 5—5 indicated in Fig. 3;

Fig. 6 is an electrical circuit diagram of the embodiment of my invention shown in Figs. 1—5;

20 Fig. 7 is an end elevation view partly in section of a modified form of my invention;

Fig. 8 is a fragmentary side elevation view of the modified embodiment shown in Fig. 7; and

25 Fig. 9 is an electrical circuit diagram of the embodiment of my invention shown in Figs. 7 and 8.

Referring to Figs. 1—5, the preferred embodiment of my invention comprises a shaft 10 which is manually rotatable, such as by a knob 11, and which is rotatably mounted in a pair of brackets 12 and 13. The brackets 12 and 13 may be mounted on a base 14 to which the brackets are secured by any suitable fastening means, such as screws 15.

30 Longitudinal displacement of the shaft 10 is prevented by collars 16 and 17 which are secured to the shaft 10 and which are rotatable therewith. The collars 16 and 17 bear against the brackets 12 and 13 and have reduced portions thereon which carry arms 18 and 19. The arms 18 and 19 preferably are formed from insulating material and may, for example, be pressed on the reduced portions of the collars 16 and 17 so as to be 35 rotatable with the collars 16 and 17 and the shaft 10. At their outer extremities, the arms 18 and 19 have apertures into which a shaft 20 may be inserted. The shaft 20 may be held in the apertures in the arms 18 and 19 by means of a bifurcated washer 21 which engages notches in the shaft 20 and by a shoulder 22 at one end of the shaft. Thus, when the shaft 10 is rotated, the shaft 20 revolves about the axis of the shaft 10.

40 45 50 55 A hollow coil form 23 having the shape of a

portion of a toroid is mounted on the base 14 by means of an insulating block 24 which may be secured to the base 14 by a screw 25 threaded into the insulating block 24. The coil form 23 is preferably formed from two substantially identical members 26 and 27 of insulating material. Each member 26 and 27 may have a substantially semi-circular cross section and when placed together form a portion of a cylindrical toroid.

The insulating mounting block 24 may be formed from two members 28 and 29 of insulating material which clamp the members 26 and 27 together and the members 28 and 29 may be pressed together by any suitable fastening means, such as rivets 30 and 31. The members 28 and 29 may have grooves therein which are semi-circular in cross section and which snugly receive the members 26 and 27 of the coil form 23.

A pair of coils 32 and 33 are mounted on the coil form 23 and also have the shape of a portion of a toroid. The coils 32 and 33 may be considered as two separate coils or may be considered as a single coil comprising two spaced portions. As used in this specification and the appended claims, the word "coil" is intended to include not only a continuous untapped winding of conductive material but also a plurality of windings of the same or different conductive material or arrangement, the windings being connected electrically in series. As shown, the coil 32 has a fewer number of turns than the coil 33 and the strip material used for the turns of coil 32 has a greater cross section than the strip material used for the turns of the coil 33. The coils 32 and 33 illustrated in the drawings have been constructed so as to provide a tuner which will tune over a pair of widely separated frequency bands. However, the coils 32 and 33 may have other arrangements or constructions well known to those skilled in the art for the purpose of tuning over different frequency bands which may be adjacent to each other or widely separated.

A third coil 34 may be wound about both of the coils 32 and 33 for the purpose of loading the coils 32 and 33 or for the purpose of coupling other circuits to the coils 32 and 33. Preferably, the coil 34 is separated from the coils 32 and 33 by a layer 35 of insulating material, such as insulating tape, which may be wound about the coils 32 and 33.

A magnetic core 36 having the same center of curvature as the coil form 23 and the coils 32, 33 and 34 is mounted coaxially with the shaft 10 and with a portion thereof inside the coil form 23. The core 36 is similar to the core described in the co-pending application Serial No. 101,713 of Lyman G. Ketcham, filed June 28, 1949, and is preferably a complete toroid, as shown, but may be discontinuous and have the shape of a portion of a toroid. The core 36 has a first portion 37 of magnetic material of relatively low conductivity which in the drawings is shown within the coil form 23. The remaining portion 38 of the core 36 has a relatively high conductivity for purposes which will be hereinafter described. Preferably, the core 36 is constructed by first forming a toroidal core of powdered magnetic material in a well known manner, the particles of magnetic material being insulated from each other. The core 36 may, for example, be formed from a mixture of powdered iron in a resin binder. After the core 36 is formed, the portion 38 is coated with a layer 39 of a material having a high conductivity, such as silver, copper, or aluminum. In the embodiment shown, the layer 39 of material of high con-

ductivity covers substantially one half of the core 36 in the circumferential direction lying in the plane of rotation of the core 36.

Preferably, the core 36 slides within the coil form 23 and may be rotated by an arm 40 which engages the shaft 20 and which may be cemented to the core 36 in a notch therein. However, if desired, the core 36 may be of such a size that a small space is left between the core 36 and the interior wall of the coil form 23 and the core 36 may be entirely supported from the shaft 10 so as to avoid frictional contact between the core 36 and the coil form 23.

When the portion 37 of low conductivity and high permeability is within the coils 32 and 33, these coils have the highest value of inductance. When, however, the high conductivity portion of the core 36 is within the coils 32 and 33, these coils have the lowest value of inductance. Accordingly, as the core 36 is rotated, the inductance of the coils changes continuously from a high value to a low value and if the coils are merely connected in series, they will act as a tuned circuit which may be tuned over a single wide frequency band. However, in accordance with my invention, provisions are made for rendering one of the coils inoperative during the passage of a predetermined portion of the core through the other of the coils.

Referring particularly to Figs. 1 and 2, it will be seen that one end of the coil 32 is connected to one terminal of a padding condenser 41, the other end of the condenser 41 being connected to a grounding lug 42. The other end of the coil 32 is connected to a stationary contact 43 mounted on the insulating block 24. One end of coil 33 is also connected to the stationary contact 43 and the other end of coil 33 is connected to a second stationary contact 44 which is also connected to a grounding lug 45. The coils 32 and 33 are, therefore, connected in series with each other and the two series connected coils are connected in parallel with the padding condenser 41.

A movable contactor 46 of conductive material, such as copper, brass, etc., is mounted on an insulating disc 47 which in turn is mounted on the shaft 10 and has an arm portion 48 which engages the shaft 20. The contactor 46 may be fastened to the insulating disc 47 by means of rivets 49 and as the shaft 10 is rotated, the insulating disc 47 and the contactor 46 are rotated therewith.

The contactor 46 has two arcuate portions 50 and 51 which extend different distances radially from the axis of the shaft 10. The stationary contacts 43 and 44 also have different lengths so that the stationary contact 44 maintains contact with the contactor 46 at all times. However, the stationary contact 43 engages the contactor 46 only when the arcuate portion 50 is rotated so as to be directly underneath the contact 43. The arcuate portion 50 is so disposed with respect to the conductive layer 39 on the portion 38 of the core 36 that it engages contact 43 as the portion 38 enters the coil 32 and remains in engagement with the contact 43 during movement of the portion 38 through the coil 32. It will be seen, therefore, that with the arrangement shown in Figs. 1 and 2, the two coils 32 and 33 during approximately 90 degrees of rotation of the shaft 10 act as a single coil, a portion of which has a continuously decreasing inductance during the rotation of the shaft 10. As soon as the portion 50 engages the stationary contact 43, the coil 33 is rendered inoperative by virtue of the connection between the stationary contact 43, the contactor 46 and the stationary contact 44 which short-

circuits the coil 33. During the remaining rotation of the shaft 10 in the clockwise direction as viewed in Fig. 2, only the coil 32 is effective and its inductance is continuously decreased from the value of inductance at the time the portion 59 engages the contact 43.

The electrical operation of the invention may be better understood by referring to Fig. 6 which shows an electrical diagram of the embodiment shown in Figs. 1-5. As shown in Fig. 6, the coils 32 and 33 both have a variable inductance and the coil 33 is short-circuited during one portion of the rotation of the shaft 10. During one portion of the rotation of the shaft 10, the circuit resonates at a frequency determined by the sum of the inductance of the coils 32 and 33, the stray capacities of the circuit, and the condenser 41. However, as soon as the contacts 43 and 44 are connected together by the contactor 46, the frequency of resonance is determined by the inductance of the coil 32 alone, the stray capacities of the circuit, and the condenser 41. Accordingly, during one portion of the rotation of the shaft 10, the circuit tunes over a wide band of relatively low frequencies and after the coil 33 is short-circuited, the circuit tunes over a wide band of relatively high frequencies.

It will be noted in connection with the description given above, that the band of relatively low frequencies is not independent of the coil 32. Therefore, as the number of turns and the spacing of the turns of the coil 32 are varied to adjust the band of frequencies covered by the coil 32, the band of frequencies covered by the coils 32 and 33 connected in series will also be varied. If it is desired to make the tuning of the circuit over the band of relatively low frequencies independent of the tuning of the coil 32, the embodiment shown in Figs. 1-5 may be modified, as shown in Figs. 7 and 8.

The modified embodiment shown in Figs. 7 and 8 differs from the embodiment shown in Figs. 1-5, substantially only in the shape of the contactor employed and by the addition of a third stationary contact which engages the contactor. The contactor 52 shown in Figs. 7 and 8 has three arcuate portions 53, 54 and 55, the portions 53 and 55 extending substantially the same distance radially from the axis of the shaft 10 and the portion 54 extending a shorter distance radially from the axis of the shaft 10. A stationary contact 56 is mounted on an insulating block 57 and is engageable with the portion 55. The insulating block 57 may be held on the base 14 by any suitable fastening means, such as screws 58. One end of the coil 32 is connected to the stationary contact 56 and the other end of the coil 32 is connected to a stationary contact 59 which is longer than the contact 56. One end of the coil 33 is also connected to the contact 59 and the other end of the coil 33 is connected to a stationary contact 60 which is engageable with the portion 53 of the contactor 52 but which cannot engage the portion 54 of the contactor 52.

During approximately the first 90 degrees of rotation of the shaft 10 from the position shown in Fig. 7, the coil 32 is rendered inoperative by virtue of the connection between the contact 56 and the portion 55 of the contactor 52 and between the contact 59 and the portion 54. However, during this portion of rotation of the shaft 10, the coil 33 is operative and the resonant frequency of the circuit is determined by the inductance of the coil 33, the stray capacities of the circuit, and the padding condenser 41. During

the remaining portion of the rotation of the shaft 10, the coil 33 is rendered inoperative by virtue of the connection between the contacts 59 and 60 and the portion 53 of the contactor 52, and the coil 32 in conjunction with the stray capacities of the circuit and the condenser 41 determines the resonant frequency of the circuit. The coil 32 is operative during the remaining portion of rotation of the shaft 10 because the contact 56 is out of engagement with the contactor 52.

Referring to Fig. 9, which shows an electrical diagram of the embodiment illustrated in Figs. 7 and 8, it will be seen that during one portion of the rotation of the shaft 10, the resonant frequency of the circuit may be continuously varied by the inductance coil 33 and during the remaining portion of the rotation of the shaft 10, the resonant frequency of the circuit may be continuously varied by the inductance coil 32. The arrangement in Figs. 7 and 8 accordingly provides a tuned circuit which is continuously variable over two wide frequency bands and each coil forming part of the tuned circuit may be adjusted substantially without affecting the band of frequencies over which the circuit may be tuned when the other coil is operative.

Having thus described my invention with particular reference to the preferred form thereof and having shown and described certain modifications, it will be obvious to those skilled in the art to which the invention pertains, after understanding my invention, that various changes and other modifications may be made therein without departing from the spirit and scope of my invention, as defined by the claims appended hereto. The number and arrangement of the stationary contacts and the shaping and arrangement of the stationary contactor may, for example, be modified so as to provide other connections of the coils which determine the frequency bands over which the circuit may be tuned. Furthermore, one or more of the tuners shown in the various figures may have their shafts mechanically connected together and may be used to tune concurrently one or more stages of an amplifier or receiver.

What is claimed as new and desired to be secured by Letters Patent of the United States is:

1. A multi-band tuner comprising a coil element; a core element mounted adjacent said coil element, said core element having a first portion of magnetic material of low conductivity and a second portion of relatively high conductivity and said core element and said coil element being movable with respect to each other; means for moving one of said elements with respect to the other of said elements; and switch means connected to said coil element and adapted to switch a portion of said coil element out of circuit with another portion of said coil element, said switch means being connected with said moving means and being operated thereby in the position thereof in which a predetermined one of said portions of said core element is adjacent said other portion of said coil element.

2. A multi-band tuner comprising a coil, a core of magnetic material of relatively low conductivity mounted with a portion thereof within said coil, said core being movable within said coil and having a layer of material of relatively high conductivity covering a predetermined portion of the length of said core; means for moving said core with respect to said coil; and switch means connected to and adapted to short-circuit a portion of said coil, said switch means being operated by said moving means during movement

of said high conductivity layer through the remainder of said coil.

3. A multi-band tuner comprising a pair of spaced coils; a core of magnetic material of relatively low conductivity mounted with a portion thereof within said coils; said core being movable within said coils and having a layer of material of relatively high conductivity on a predetermined portion of the length of said core; means for moving said core with respect to said coils; and switch means connected to one of said coils and adapted to short-circuit said one coil, said switch means being operated by said moving means during movement of said high conductivity layer through the other of said coils.

4. A multi-band tuner comprising a pair of coils mounted in spaced positions with respect to each other, said coils being connected in series with each other; a core of magnetic material of low conductivity mounted with a portion thereof within said coils, said core being movable within said coils and having a layer of material of high conductivity on a predetermined portion of the length of said core; means for moving said core; a pair of stationary contacts, one being connected to the adjacent connected ends of said coils and the other being connected to the opposite end of one of said coils; and means controlled with said moving means and adapted to interconnect said stationary contacts while said high conductivity layer is within the other of said coils.

5. A multi-band tuner comprising a coil element having the shape of a portion of a toroid; a core element mounted adjacent said coil and having the shape of at least a portion of a toroid, said core element having a first portion of magnetic material of low conductivity and a second portion of relatively high conductivity and said core element and said coil element being movable with respect to each other; means for moving one of said elements with respect to the other of said elements; and switch means connected to said coil element and being adapted to switch a portion of said coil element out of circuit with another portion of said coil element, said switch means being operated by said moving means during relative movement of a predetermined one of said portions of said core element past said other portion of said coil element.

6. A multi-band tuner comprising a pair of coil elements, each having the shape of a portion of a toroid; a core element mounted adjacent said coil elements and having the shape of at least a portion of a toroid, said core element having a first portion of magnetic material of low conductivity and a second portion of relatively high conductivity and said core element and said coil elements being movable with respect to each other; means for moving one of said elements with respect to the other of said elements; and switch means connected to one of said coil elements and adapted to switch said one coil element out of circuit with the other of said coil elements, said switch means being operated by said moving means during relative movement of a predetermined one of said portions of said core element past the other of said coil elements.

7. A multi-band tuner comprising a coil having the shape of a portion of a toroid; a core mounted adjacent said coil and having the shape of at least a portion of a toroid, said core having a first portion of magnetic material of low conductivity and a second portion of relatively high

conductivity and said core and said coil being movable with respect to each other; means for rotating said core and said coil relative to each other; and switch means connected to said coil and adapted to switch a portion of said coil out of circuit with another portion of said coil, said switch means being operated by said rotating means during relative movement of a predetermined one of said portions of said core past the remainder of said coil.

8. A multi-band tuner comprising a pair of coils having the shape of a portion of a toroid; a core mounted adjacent said coils and having the shape of at least a portion of a toroid, said core having a first portion of magnetic material of low conductivity and a second portion of relatively high conductivity and said core and said coils being movable with respect to each other; means for rotating said core and said coils relative to each other; and switch means connected to one of said coils and adapted to switch one of said coils out of circuit with the other of said coils, said switch means being operated by said rotating means during relative movement of a predetermined one of said portions of said core past said other of said coils.

9. A multi-band tuner comprising a coil having the shape of a first portion of a toroid; a core having a portion of magnetic material of relatively low conductivity and having the shape of at least a portion of a toroid, said core being mounted adjacent said coil and said core and said coil being movable with respect to each other, a layer of material of relatively high conductivity on a second portion of said core and covering a predetermined length thereof in a circumferential direction; means for rotating said core and said coil relative to each other; and switch means connected to said coil and adapted to switch a portion of said coil out of circuit with the remainder of said coil, said switch means being operated by said rotating means during relative movement of a predetermined one of said portions of said core past said remainder of said coil.

10. A multi-band tuner comprising a pair of coils having the shape of a portion of a toroid; a core of magnetic material of relatively low conductivity having the shape of at least a portion of a toroid and mounted with a portion thereof adjacent said coils; said core and said coils being movable with respect to each other and said core having a layer of material of relatively high conductivity thereon covering a predetermined length thereof in a circumferential direction; means for rotating said core and said coils relative to each other; and switch means connected to one of said coils and adapted to switch one of said coils out of circuit with the other of said coils, said switch means being operated by said rotating means during relative movement of a predetermined portion of said core past the other of said coils.

11. A multi-band tuner comprising a coil having the shape of a portion of a toroid; a toroidal core of magnetic material of relatively low conductivity mounted with a portion thereof adjacent said coil, said core having the same center of curvature as said coil and being movable with respect thereto and a layer of material of relatively high conductivity on said core covering a predetermined length of said core in a circumferential direction; means for rotating said core about its center of curvature; and switch means connected to said coil and adapted to switch a

portion of said coil out of circuit with the remainder of said coil, said switch means being operated by said rotating means during movement of said high conductivity layer past said remainder of said coil.

12. A multi-band tuner comprising a pair of coils having the shape of a portion of a toroid; a toroidal core of magnetic material of relatively low conductivity mounted with a portion thereof adjacent said coils, said core having the same center of curvature as said coils and being movable with respect thereto and a layer of material of relatively high conductivity on said core covering a predetermined length of said core in a circumferential direction; means for rotating said core about its center of curvature; and switch means connected to one of said coils and adapted to switch one of said coils out of circuit with the other of said coils, said switch means being operated by said rotating means during movement of said high conductivity layer past said other of said coils.

13. A multi-band tuner comprising a coil having the shape of a portion of a toroid; a toroidal core of magnetic material of relatively low conductivity mounted with a portion thereof within said coil, said core having the same center of curvature as said coil and being movable therein and a layer of material of relatively high conductivity on said core covering a predetermined length of said core in a circumferential direction; means for rotating said core about its center of curvature; and switch means connected to said coil and adapted to short-circuit a portion of said coil, said switch means being operated by said rotating means during movement of said high conductivity layer through the remainder of said coil.

14. A multi-band tuner comprising a pair of spaced coils having the shape of a portion of a toroid; a toroidal core of magnetic material of relatively low conductivity mounted with a portion thereof within said coils, said core having the same center of curvature as said coils and being movable therein and a layer of material of relatively high conductivity on said core covering a predetermined length of said core in a circumferential direction; means for rotating said core about its center of curvature; and switch means connected to one of said coils and adapted to short-circuit said one of said coils, said switch means being operated to its short-circuiting position by said rotating means during movement of said high conductivity layer through the other of said coils.

15. A multi-band tuner comprising a pair of coils having the shape of a portion of a toroid mounted in spaced positions with respect to each other, said coils being connected in series with each other; a toroidal core of magnetic material of low conductivity mounted with a portion thereof within said coils, said core having the same center of curvature as said coils and being movable therein and a layer of material of high conductivity on said core covering a length of said core in a circumferential direction equal to the length of one of said coils; a rotatable shaft mounted at the center of curvature of said core and perpendicular to the plane of said core and means connecting said core to said shaft; a pair of stationary contacts, one being connected to the adjacent connected ends of said coils and the other being connected to the opposite end of the other of said coils; and means controlled with said shaft for interconnecting said stationary

contacts while said high conductivity layer is within said one coil.

16. A multi-band tuner comprising a hollow coil form of insulating material having the shape of a portion of a toroid, a pair of coils having different reactance values mounted on said coil form in spaced positions with respect to each other, said coils being connected in series with each other; a toroidal core of magnetic material of low conductivity mounted with a portion thereof within said coil form, said core having the same center of curvature as said coil form and being movable therein and a layer of material of high conductivity on said core covering substantially one-half of said core in a circumferential direction; a rotatable shaft mounted at the center of curvature of said core and perpendicular to the plane of said core and means connecting said core to said shaft; a pair of stationary contacts, one being connected to one end of the coil of higher reactance value and the other being connected to the other end of said coil of higher reactance value; and means operable by said shaft for interconnecting said stationary contacts while said high conductivity layer is within the coil of lower reactance value, said stationary contacts being electrically unconnected at other positions of said core.

17. A multi-band tuner comprising a hollow coil form of insulating material having the shape of a portion of a toroid; a pair of coils having different reactance values mounted on said coil form in spaced positions with respect to each other, said coils being connected in series with each other; a toroidal core of magnetic material of low conductivity mounted with a portion thereof within said coil form, said core having the same center of curvature as said coil form and being movable therein and a layer of material of high conductivity on said core covering substantially one-half of said core in a circumferential direction; a rotatable shaft mounted at the center of curvature of said core and perpendicular to the plane of said core and means connecting said core to said shaft; a pair of stationary contacts, one being connected to one end of the coil of higher reactance value and the other being connected to the other end of said coil of higher reactance value; and a movable contactor mounted on said shaft, said contactor being adapted to interconnect said stationary contacts while said high conductivity layer is within the coil of lower reactance value and being out of engagement with one of said stationary contacts at other positions of said core.

18. A multi-band tuner comprising a hollow, semi-toroidal coil form comprising two substantially identical sections of insulating material each having a semi-circular cross-section; a pair of coils having different reactance values mounted on said coil form in spaced positions with respect to each other, said coils being connected in series with each other; a toroidal core of magnetic material of low conductivity mounted with a portion thereof within said coil form, said core having the same center of curvature as said coil form and being movable therein and a layer of material of high conductivity on said core covering substantially one-half of said core in a circumferential direction; a rotatable shaft mounted at the center of curvature of said core and perpendicular to the plane of said core and means connecting said core to said shaft; a pair of stationary contacts, one being connected to one end of the coil of higher reactance value and the

other being connected to the other end of said coil of higher reactance value; and a movable contactor mounted on said shaft, said contactor being adapted to interconnect said stationary contacts while said high conductivity layer is within the coil of lower reactance value and being out of engagement with one of said stationary contacts at other positions of said core.

19. A multi-band tuner comprising a hollow, semi-toroidal coil form comprising two substantially identical sections of insulating material each having a semi-circular cross-section; a pair of coils having different reactance values mounted on said coil form in spaced positions with respect to each other, said coils being connected in series with each other; a toroidal core of magnetic material of low conductivity mounted with a portion thereof within said coil form, said core having the same center of curvature as said coil form and being movable therein and a layer of material of high conductivity on said core covering substantially one-half of said core in a circumferential direction; a rotatable shaft mounted at the center of curvature of said core and

5
